DAVID E. RIGGINS, OF PERRY, OKLAHOMA.

LOCKING MEANS.

1,830,394.

Specification of Letters Patent.

Patented Feb. 10, 1920.

Application filed April 22, 1918. Serial No. 230,115.

To all whom it may concern:

Be it known that I, DAVID E. RIGGINS, a citizen of the United States, residing at Perry, in the county of Noble and State of Oklahoma, have invented certain new and useful Improvements in Locking Means, of which the following is a specification.

This invention relates to locking means, and more particularly to means for locking 10 the steering gear of an automobile so as to prevent unauthorized use of the same.

One of the main objects of the invention is to provide a locking device of simple construction and operation which may be 16 readily applied to an automobile steering gear of standard construction. A further object is to provide a lock which may be readily assembled or disassembled, in which the locking bolt may be secured in either 20 operative or inoperative position. Further objects will appear from the detailed description.

In the drawings:

Figure 1 is a side view of a locking device 25 constructed in accordance with my invention, as applied.

Fig. 2 is a longitudinal section through the lock and the adjacent portion of the standard.

Fig. 3 is a section through the lock taken substantially on line 3-3 of Fig. 2.

Fig. 4 is a fragmentary detail section taken through the standard and the adjacent portion of the lock.

A T-member 1 is formed with an integral clamp body having the outwardly directed diametrically opposite securing ears 2 which are adapted to receive securing rivets so as to secure the T-member to a tubular standard 3 of an automobile of usual construction, this standard being secured at its base to the foot-board or floor of the vehicle in the usual manner. The steering rod 4 is mounted in standard 3 so as to be operable 45 therein, steering wheel 5 being secured to the upper end of this rod. All of the parts so far described are of usual or standard construction.

A tubular bolt casing or sleeve 6 is threaded into neck 7 of T-member 1. A bolt 8 is slidably mounted in casing 6 and has its inner end portion 9 adapted to engage into a coöperating recess 10 in the rod 4, standard 3 being provided with a suitable opening which is adapted to snugly receive the inner end portion of the bolt. This bolt

is further provided with spaced radially projecting lugs 11 which are operable through a longitudinally extending slot 12 provided through casing 6. Lugs 11 correspond in height to the thickness of annular locking plates or tumblers 13 which are mounted on casing 6 so as to be turned about the same. Each of these plates is provided with an opening or slot 13^a contiguous to its central bore or opening which slot corresponds in size and shape to the lugs 11 so that, by turning the plates into such relative positions as to bring these slots into alignment, the bolt 8 may be moved either outwardly or inwardly, as desired. By changing the relative positions of the plates on sleeve 6, the numbers of the combinations may be varied, it being understood, of course, that the peripheral surfaces of the plates are numbered, certain of these numbers being in axial alignment with the slots of the plates so that, by bringing the proper numbers into alignment, the slots will also be aligned thus permitting operation of the bolt.

The innermost lug 11^a is of substantially V-shape and is adapted to fit into a corresponding recess in the inner face of the neck of the T members, when the bolt is in its innermost position, thus effectually securing the casing 6 against rotary movement in the neck of the T member. This provides a locking means which prevents detaching of casing 6 when the bolt is in its inner or operative position, while permitting this casing to be readily detached from the T member when the bolt is in retracted position, thus rendering it possible to readily and easily interchange the locking plates or tumblers so as to vary the combination. It will be understood that the lug 11^a is of such size as to fit within the slot of the innermost tumblers when the bolt is in its center position so that, by grasping the tumblers, the casing 6 may be readily turned, the first, third, and fifth tumbler being in engagement with lugs 11 and 11^a.

A closure cap 14 is secured on the outer end of casing 6 by means of securing screws 15 which are threaded through the reduced neck of the cap, as in Fig. 2. A collar 16 is mounted loosely about the neck of cap 14 and serves to prevent access to the screws thus rendering it impossible to remove the cap. This cap is provided with a central opening which slidably receives a reduced

stem 17 projecting from the outer end of the bolt. A thumb nut 18 is threaded on the outer end of this stem and provides means whereby the bolt may be pulled outwardly 5 in casing 6. A coil expansion spring 19 is mounted about stem 17 and confined between the cap and the outer end of the bolt. This coil expansion spring acts to force the bolt inwardly into locking position. In Fig. 2, the bolt is shown in locking position so as to prevent rotation of steering rod 4 thus effectually locking the steering gear against operation. If it is desired to release the rod 4, this is accomplished by turning the plates 13 so as to bring the slots thereof into alignment after which the bolt 8 is moved outwardly by means of thumb nut 18 so as to disengage element 9 from the recess 10. When moved into its outermost position, 20 the bolt will be so positioned as to have the outermost lug 11 positioned adjacent the outer end of slot 12 of casing 6 so that, by rotating the innermost plate, and the next to the outermost plate slightly, these plates 25 are brought into position inside of the lugs securing bolt 8 against inward movement so as to permit operation of steering rod 4 in the usual manner. By reversing this operation, the bolt may be positively locked in its innermost or operative position, as shown in 30 Fig. 2.

When it is desired to interchange the locking plates 13 so as to alter the combination, by grasping the plates 13, in the slots 35 of which the lugs 11 and 11^a are positioned, casing 6 may be easily rotated so as to be unscrewed from neck 7 of the T. When the casing has been thus removed, the plates 13 may be slid from the inner end of the casing, 40 so as to be removed therefrom, and may be readily replaced in any desired relative position. Also, if it is desirable or necessary to have access to the outer end of the casing, this is easily accomplished by removing 45 plate 13 and collar 16, after which the screws 15 may be removed thus permitting cap 14 to be taken from the end of the casing, thumb nut 18 being threaded off of stem 17. This construction renders it possible to readily assemble or disassemble the 50 lock for cleaning, repairs, and other purposes while also permitting the combination to be readily and easily changed when desired.

To prevent unauthorized opening of the lock, I provide each plate 13, each face, with a plurality of recesses 20 contiguous to the central opening of the plate. These recesses 20 perform two very important functions. 55 First, they act as a safety when the lock is in inoperative position or unlocked, by preventing the locking plates from being accidentally brought into proper alignment by vibration of the car or other causes which

would cause accidents. This is accomplished by turning the second or fourth plates far enough in either direction when the bolt is withdrawn to bring one of the depressions 20 in line with one of the lugs when the spring will force the bolt forward 65 slightly and the lug will engage the depression. This prevents the turning of any one of the different plates owing to the fact that the bolt being slightly shot forward, the different lugs will engage each of the 70 five different plates. None of the plates can then rotate until the bolt is again slightly withdrawn. Secondly, if there were no recesses 20 it might be possible for a thief or unauthorized person to feel out the proper 75 unlocking alignment of each plate by pulling upwardly with one hand on the opposed end of the sliding bolt and at the same time turning the plate with the thumb and finger of the other hand because there would be 80 less friction and consequently a slight vibration when the slot in the plate passes by the lug or proper alignment for unlocking. As 85 this same releasing of friction and vibration is encountered at every number, when a depression is used under each number, the most expert lock picker would be deceived. Therefore, it is self-evident that the depressions 20 on the locking plates constitute a 90 valuable feature of this invention. It is to 95 be borne in mind that the depressions 20 are on both faces of each and every plate and directly under each number. As is well known, an expert in picking locks and opening permutation locks has his sense of touch 100 very highly developed and is able to tell by the very slight vibration which takes place when these plates or disks of a lock of this character are moved into such position as to give the controlling combination, 105 when he is operating the plates properly. By providing these recesses which also cause vibration of the plate, I render it impossible or very difficult for a lock of this character to be opened in this manner.

What I claim is:

1. In locking means, a T-member adapted to be secured on the steering column of an automobile, a tubular casing removably secured in the neck of said T-member, a locking bolt slideable in the casing and provided with radially projecting lugs extending through the casing, said casing being provided with a longitudinal slot to accommodate said lugs, a closure cap mounted on the 120 outer end of said casing and provided with a reduced neck, securing screws inserted through said neck and threaded into the casing, a collar mounted about the neck of said cap and serving to cover up the securing 125 screws so as to prevent removal thereof, locking plates loosely mounted on the casing in superposed relation and confined be-

tween said collar and the neck of the T-member, the plates being provided with slots adapted to accommodate the lugs of said bolt when in alinement, and means for operating said bolt exteriorly of the casing.

2. In a device of the class described, a T-shaped tubular coupling adapted to be mounted on a steering column of an automobile, a casing threaded into the neck of said coupling, a locking bolt slideable in said casing, a closure cap on the end of said casing, said bolt having a reduced extension projecting through said cap, a coiled spring on said extension within said casing operating to normally project the bolt, spaced radially projecting lugs carried by said bolt, said casing having a longitudinally extending

slot through which said lugs operate, annular tumblers mounted on said casing and rotatable thereon, each having an opening 20 contiguous to its central bore corresponding in size and shape to said lugs to provide for releasing the bolt, said tumblers having depressions on their opposed faces adjacent the bores therein, and means carried by the 25 bolt for locking it against turning when in operative position.

In testimony whereof I affix my signature in presence of two witnesses.

DAVID E. RIGGINS.
